POWER OPERATED WINDOW REGULATOR

Emory Glenn Simpson, Detroit, Mich., assignor to
 Ternstedt Manufacturing Company, Detroit,
 Mich., a corporation of Michigan

Application June 18, 1941, Serial No. 398,559

3 Claims. (Cl. 268—19)

This invention relates to a window regulator adapted to control both a swinging window and a sliding window. Automobiles are today almost universally provided with the so-called Fisher no-draft ventilating system. This consists of a forward window panel which swings on an intermediate up and down axis and a rear vertically sliding panel. These are ordinarily controlled by separate window regulators operated by separate cranks. It is the object of the present invention to afford a power-operated window regulator mechanism which can operate both the panels. This mechanism uses one source of power and is controlled by separate switches or buttons. The same driving and power connections operate both mechanisms and the selective operation of each is controlled by a suitable clutch.

In the drawings:

Fig. 1 is an elevation of the apparatus with a diagram of the wiring.

Fig. 2 is a side elevation of the apparatus taken at 90 degrees from Fig. 1.

Figs. 3 and 4 are sections taken on the corresponding lines of Fig. 2.

Fig. 5 is an elevation of the upper part of the apparatus taken from the right of Fig. 2.

Fig. 6 is a section taken on the section line 6—6 of Fig. 5.

Fig. 7 is a section taken on the line 7—7 of Fig. 5.

Fig. 8 is a plan view looking down on the top of the mechanism shown in Fig. 5.

Fig. 9 is a section on the line 9—9 of Fig. 5.

Referring to Fig. 1 numeral 1 designates the usual swinging panel used in the front of a front door in the Fisher no-draft ventilating system. 2 represents the sliding panel. This sliding panel is guided vertically in window runs not shown and is raised and lowered by a cable type of regulator provided with a lift pin 3 which engages in the notch 5 in the window bracket 4. The pin is locked in this notch by means of the hook 6 which has a notch 7. The cable 8 passes over the upper sheave 9 and over the lower sheave 10 which is supported on a slide 11 which is spring-pressed by spring 12 to put the cable under tension. The cable passes also over the idling sheaves 13 and 14 and then passes horizontally to the left where it passes over the driving pulley 15.

Refer to Fig. 2. This driving pulley 15 has a helical groove around which the cable winds. This pulley is bolted on the shaft 16 which is supported in ball bearing 17. This shaft carries a worm wheel 18. On the end of the shaft is a

spiral counterbalancing spring 19, one end of which as at 20 is secured to the shaft and the other end secured to the gear housing 21. The worm wheel is driven by worm 22. Worm 22 is supported loosely on shaft 23. This is the motor shaft. On the upper end of the shaft a worm 24 fits loosely and meshes with the worm gear 25 which is keyed on worm shaft 26 (Fig. 6). Also keyed on this shaft is a second worm 27 which meshes with the worm gear 28. This worm gear is a part of a casting 29 (Fig. 9) which forms a journal for the gear and is rotatably supported in housing 30. The top of this journal is slotted as at 31 to receive the flattened spindle 32 which is connected to the bottom of the swinging panel 1.

The two driving worms 22 and 24 drive the cable regulator and the C. V. regulator, respectively, and are coupled to the drive shaft by means of a jaw clutch 33. Here it might be explained that the swinging panel regulator is called the "C. V. regulator", because this is how it is designated in the Fisher no-draft ventilating system—the "C. V." is an abbreviation for "Controlled ventilation." Clutch 33 has a slidable clutch sleeve 34 with teeth at each end arranged to engage in notches 35 in the worm 24 or notches 36 in the end of worm 22. This sleeve is splined on the drive shaft 23 by means of spline 37. This sleeve is ordinarily in a neutral position as shown in Fig. 7, but it can be shifted either to engage worm 22 or worm 24 by means of the shiftable armature 38. This armature 38 can be shifted one way or the other by the two solenoids 39 and 40. On the end of the armature is a roller 41 which engages in the annular groove 42 on the outside of the clutch sleeve. Armature 38 is slidably guided on post 43 and is normally kept in a central position by springs 44 and 45.

Shaft 23 is driven by motor M. Motor M is controlled by two circuits, one connecting with switch buttons adjacent the C. V. panel, one button to control the circuit that will rotate the motor armature in one direction, the other button to control the circuit to rotate the motor armature in the opposite direction. Each of these circuits passes through the solenoid 39 which urges the clutch to drive the worm 24. In each of these C. V. regulator circuits are limit switches 46 and 47 which are operated by cam 48 on the C. V. panel spindle 32. There are also two circuits in connection with the cable regulator controlled by switch buttons located adjacent the sliding panel, one circuit serves to rotate the motor in one direction and the other circuit the motor in the

opposite direction. Limit switches 49 and 50 can be located in these circuits and thereby break the current when the sliding panel reaches the limit of its travel either up or down.

Referring to Fig. 1 the wiring diagram will be found. Switch 52 is pivoted at 51 and adapted to control the two sliding panel circuits referred to above. Rotating the switch 52 in a counterclockwise direction will close the circuit from battery B through wire 53, wire 54, limit switch 49, motor M, ground 60 and ground 61 on the battery. This causes the motor to rotate in a direction to lower the slide panel. At the same time, current will flow from wire 53 through switch 52, wire 62, solenoid 40, ground 63 and back to ground 61 on the battery to energize solenoid 40 which couples the motor with the worm 21 to drive the cable regulator. When the window reaches the lowermost limit of its travel, it can break the circuit at the limit switch 49. Rotating switch 52 in a clockwise direction will set up a circuit through wire 53, wire 64, limit switch 50, wire 65, motor M, ground 60 and ground 61. At the same time, current will flow from wire 53 through wire 62, solenoid 40, ground 63 and ground 61 to energize the solenoid 40 to couple the motor with the worm 21. In this circuit with current passing through line 65 instead of line 54 into the motor, the motor is rotated in a direction to raise the window. When the window reaches the upper limit of its movement it will break the circuit at limit switch 50.

To control the C. V. ventilator a switch 66 is pivoted at 67. Rotating switch 66 in a clockwise direction will establish a circuit from battery B through wire 68, wire 69, limit switch 46, motor M, ground 60 and ground 61. At the same time, current will flow from wire 68 through wire 70, solenoid 39, ground 71 and ground 61. By energizing this circuit the motor will be rotated to turn the C. V. ventilator outwardly and the solenoid 39 is energized to urge the clutch to drive the worm 24. When cam 48 strikes limit switch 46, the circuit will be broken and the motor stopped. When the switch 66 is rotated in a counterclockwise direction a circuit is established from battery B through line 68, line 72, limit switch 47, motor M, ground 60 and ground 61. At the same time, current flows from line 68 through line 70, solenoid 39, ground 71 and ground 61. This will turn the rear end of the ventilator panel in and close the window. Cam 48 will strike limit switch 47 and break the circuit to stop the motor.

The control switches 52 and 66 can be located at any convenient point on the body or on the instrument board. The solenoid, if desired, can be used in connection with a single manually operated handle to operate either the C. V. member or the sliding member.

What I claim is:

1. In a window regulator for operating a swinging panel and a sliding panel in a no-draft ventilating system, a mechanism for turning the swinging panel, a mechanism for raising and lowering the sliding panel, the two mechanisms including worms, a drive shaft upon which the worms are loosely supported, a clutch member splined on the drive shaft and adapted to be shifted into end-to-end engagement with either of the worms to selectively drive either of the regulators, an armature engaging said clutch member to shift the same, and two solenoids for shifting the armature in either direction to couple the driving shaft with either worm, a motor for driving said shaft, and switches, one switch for controlling the direction of the motor and, at the same time, one solenoid to shift the clutch to engage one worm, and the other switch controlling the direction of the rotation of the motor and the other solenoid to shift the clutch to operate the other worm.

2. In a window regulator for operating a swinging panel and a sliding panel in a no-draft ventilating system, the combination of a worm and gear mechanism for turning the swinging panel, a cable type of regulator for raising and lowering the sliding panel and having a portion of the cable diverted from the usual up and down path to a point adjacent the worm and gear mechanism for turning the swinging panel, a power operated driving member and a remote electromagnetically controlled coupling member shiftable to put the driving member into driving connection with the cable regulator, or shiftable to put the driving member into driving connection with the worm and gear regulator.

3. In a window regulator for operating a swinging panel and a sliding panel in a no-draft ventilating system, the combination of a worm and gear mechanism for turning the swinging panel, a cable type of regulator for raising and lowering the sliding panel and having a portion of the cable diverted from the usual up and down path of the cable regulator to a point adjacent the worm and gear mechanism for turning the swinging panel, a driving member, a coupling member shiftable to put the driving member into driving connection with the cable regulator, or shiftable to put the driving member into driving connection with the worm and gear type regulator, an electric motor for driving the shaft, solenoids for shifting the coupling, and control circuits and switches for simultaneously energizing the motor and the solenoids selectively to determine the direction of rotation of the motor and the proper solenoid to operate the desired regulator.
